APPLICATIONS**

This application is a continuation-in-part of copending application Ser. No. 770,964, filed Oct. 28, 1968 and now abandoned. Copending applications Ser. No. 75,009, Ser. No. 75,037, and Ser. No. 75,067, filed Sept. 24, 1970, also are continuations-in-part of that application and claim subject matter related to that claimed herein.

BACKGROUND OF THE INVENTION

1. Field of the Invention

This invention relates to the recovery of hydrocarbons and optionally nahcolite from underground oil shale formations containing nahcolite deposits. More particularly, it relates to hydrocarbon recovery by in-situ thermal fluid extraction of oil shale within a fracturized and/or rubblized portion of a subterranean oil shale formation in and around a cavern and interconnected cavities formed by leaching or dissolving, e.g., solution mining of the nahcolite therefrom.

2. Description of the Prior Art

Large deposits of oil in the form of oil shale are found in various sections of the United States, particularly in Colorado and surrounding states and Canada. Various methods of recovery of oil from these shale deposits have been proposed and the principal difficulty with these methods is their high cost which renders the recovered oil too expensive to compete with petroleum crudes recovered by more conventional methods. Mining the oil shale and removing the oil therefrom by above-ground retorting in furnaces presents a disposal and pollution problem and also such processes are also generally commercially uneconomical. In-situ retorting to convert the oil shale to recover the oil contained therein is made difficult because of the non-permeable nature of the oil shale. The art discloses various means of improving oil recovery of oil from oil shale such as described in U.S. Pat. Nos. 3,400,762 or 3,437,378, or 3,478,825 and particularly various means of increasing permeability of oil shale formations as described in U.S. Pat. Nos. 3,273,649 or 3,481,398 or 3,502,372, or copending application Ser. No. 839,350, filed July 7, 1969. Although these references are directed to an advancement of the art, the basic technique for recovering oil from oil shale still requires rubblization techniques such as by means of explosive devices, e.g., nuclear energy which are expensive, difficult to control and presents a radioactive contamination problem all of which are very undesirable.

OBJECTS OF THE INVENTION

It is an object of this invention to provide an improved method for recovering hydrocarbons from a nahcolite containing oil shale formation by leaching or dissolving the water-soluble minerals such as by solution mining so as to form a cavern and/or interconnected cavities within the oil shale formation.

It is a further object of the invention to effect rubblization and/or fracturization of the nahcolite leached oil shale formation surrounding the cavern and/or cavities so as to form a permeable zone thereby enhancing in-

situ thermal fluid extraction (pyrolysis) of hydrocarbons therefrom.

Still another object of this invention is to effect in-situ pyrolysis to produce hydrocarbons from oil shale subjected to leaching, rubblization and fracturization as indicated in the previous two paragraphs, and subsequently recovering the hydrocarbons by suitable means.

Still another object of the present invention is to recover water-soluble minerals from a rich nahcolite containing oil shale formation that may be removed during the leaching and/or solution mining, rubblization and/or fracturization, and/or pyrolysis processes.

Still another object of the present invention is to sequentially and/or simultaneously recover nahcolite and hydrocarbons from nahcolite containing oil shale formations that may be removed during the leaching and/or solution mining, rubblization and/or fracturization and/or pyrolysis processes.

Other objects of the invention will be apparent from the following description.

SUMMARY OF THE INVENTION

The present invention is directed to recovery of hydrocarbons and optionally nahcolite from a nahcolite containing oil shale formations by the following steps: (1) subjecting a rich nahcolite zone(s) of an oil shale formation to a leaching, dissolving or solution mining process so as to remove the nahcolite, thereby creating porosity to allow for thermal expansion of the oil shale and establish communication through the treated zone(s), (2) effecting in said leached zone(s) rubblization and/or fracturization so as to form zone(s) of rubblized and/or fractured oil shale with large surface area for more efficient heat treatment by in-situ thermal fluid extraction (pyrolysis) and (3) injecting into the rubblized and/or fracturized oil shale zone(s) a pyrolyzing fluid to effect hydrocarbon recovery.

The nahcolite and hydrocarbons may be recovered sequentially or simultaneously and if the latter, the two products can be separated by suitable means such as settling or solvent extraction above ground. The oil shale formation may contain more than one zone of rich nahcolite which zones may be separated by impermeable oil shale layers of several feet to several hundred feet and each of these nahcolite layers or zones can be leached or dissolved or solution mined in accordance with the process of the present invention.

The first or initial step should be so designed to create a cavern or interconnecting cavities in the nahcolite bed(s) or zone(s) by dissolving, leaching or solution mining techniques through at least one borehole penetrating said formation. Leaching can be effected by cold or hot aqueous solutions either at atmospheric or elevated pressures. When hot solutions are used such as hot water and/or steam, more rapid dissolution is effected to produce void spaces in the oil shale formation thereby providing and enhancing well communication, space for thermal expansion of the shale, and greater surface for contact with subsequent pyrolyzing fluid.

If necessary, fracturing the formation either before or after leaching by conventional means such as hydrofracturing, explosive means, nuclear means, etc., may be desirable. The leaching solutions can contain chemical agents to enhance dissolution of the minerals. Under certain leaching conditions decomposition of nahcolite, into solubilizing materials may take place for

such minerals as dawsonite and silicates which might be present in the formation, thereby increasing the porosity of the formation. For example, when nahcolite is dissolved with water, the pH of the dissolution fluid is increased and thereby aids in the dissolution of silicates, etc.

Leaching or solution mining of nahcolite can be accomplished by a suitable solution mining technique such as described in U.S. Pat. Nos. 2,618,475; 3,387,888; 3,393,013; 3,402,966; 3,236,564; 3,510,167; or Canadian Pat. Nos. 832,828 or 832,276 or as described in copending application Ser. No. 2,765, filed Jan. 14, 1970. Spalling and rubblization can be accomplished by the method described in U.S. Pat. No. 3,478,825 or by other means such as by hydraulic explosive, nuclear, means. Preferably rubblization is accomplished by hot fluid circulation through two caverns causing the walls to spall and fracture. In-situ thermal recovery of oil can be effected by a pyrolyzing fluid such as steam and/or hot water or solvent extraction means.

The circulation of a pyrolyzing fluid not only effects oil recovery but and also effects thermal rubblization and/or fracturization. Also, if the pyrolyzing fluid such as steam is used to extract and recover oil, more nahcolite may be dissolved perpetuating the process.

The term "pyrolyzing fluid" is used to refer to a liquid or gas which by means of thermal, chemical and/or solvent action, interacts with the kerogen components of an oil shale to produce and entrain hydrocarbon such as oil. Such a fluid can be comprised of hot fluids such as hot water or steam or a mixture of hot water and steam, hot hydrocarbons and/or mixtures of such fluids with chemicals such as organic solvents, benzene, toluene, cumene, phenol, etc. The kerogen pyrolyzing fluid can be heated by surface or borehole-located heating devices. The kerogen-pyrolyzing fluid can advantageously comprise or contain a solvent for the nahcolite such as a steam condensate having a temperature such as at least 100° Fahrenheit, such as from about 450°F to above about 1,500°F and preferably from about 550°F to 1,000°F. Where the kerogen-pyrolyzing fluid contains or forms aqueous components, its circulation through the treated oil shale formation can enlarge the cavern, by solution mining the soluble materials, while shale oil is being produced. Also, simultaneously or sequentially soluble and insoluble pyrolyzing and oil extracting fluids can be used such as steam followed by a solvent such as phenol or benzene.

BRIEF DESCRIPTION OF THE DRAWINGS

FIG. 1 is a vertical sectional view, partly diagrammatic, of an embodiment of the invention showing a formation penetration by more than one well; and

FIG. 2 is a sectional view of an embodiment of the invention, the formation being penetrated by a single well.

DESCRIPTION OF THE PREFERRED EMBODIMENT

Referring to FIG. 1 we see a subterranean oil shale formation, 9, which contains rich zones of nahcolite 10, 10a and 10b. An injection well borehole 11 and production borehole 12 are shown extending into oil shale formation 9 and rich nahcolite zone(s) 10 or multi-zones such as 10a and 10b that are located within the oil shale formation 9. Well boreholes 11 and 12 are il-

lustrated as having casings 13 through 14, respectively, cemented in place in their respective boreholes by suitable sealants 15 through 16, respectively. Although only a single injection well borehole 11 and a single production well borehole 12 have been illustrated, obviously various combinations of one or more injection and production wells may be provided by one skilled in the art.

Fluid communication between well boreholes 11 and 12 (FIG. 1) and the zones rich in nahcolite therebetween may be established by solution mining a cavern or cavities 23, through the soluble mineral zones. Communication can be enhanced by means of conventional hydraulic, electric, and/or explosive fracturing techniques, all well known in the art. Where, for example, subterranean stresses in and around soluble mineral zones 10, 10a and 10b are conducive to the formation of horizontal fractures, the fluid communication between well boreholes 11 and 12 and the nahcolite can be established by conventional hydraulic fracturing techniques. Referring to FIG. 1, after fluid communication has been established between a pair of wells, aqueous leaching or solution mining liquid is injected through tubing 17 down well borehole 11, out through perforations 18 opposite any or all of the soluble beds through the bed 10, 10a and/or 10b up borehole 12 through tubing 17 via perforation 19 creating a leached cavern 23. The aqueous liquid may comprise water and/or steam or aqueous solutions and is circulated at pressures either above or below the over-burden pressure. The circulating aqueous liquid dissolves the nahcolite which is recovered from the fluid flowing out of well borehole 12, for example, by conventional evaporation and/or precipitation procedures.

Fluid communication can also be established in one borehole between at least two spaced portions of the well borehole and nahcolite (as for example, in FIG. 2, communication is through the tubing string the ends of which are open to the nahcolite and some distance apart.) Thus, a single well may be utilized by a dual-zone completion arrangement as shown in FIG. 2 such that fluids can be injected at one point of the well and produced from another point of the same well. In FIG. 2, the wellbore is 26, the casing is 27, the sealant is 28, within the casing are the injection tubing string 29 and production tubing string 30, the borehole 26 penetrates oil shale formation 9 with nahcolite zone(s) 10 or multizones 10a and 10b.

Fracturing pressures are generated within the oil shale formation 9 while lower pressures are maintained within the cavern 23 which is formed within oil shale formation 9 by the removal of nahcolite. These pressures are preferably generated by merely circulating hot fluid through cavern 23. As the walls of the cavern(s) 23 (23a FIG. 2) are heated kerogen is pyrolyzed within the cavern walls and the pressures of the pyrolysis products increase until portions of the walls are spalled into the cavern 23 creating a rubblized zone 24 (24a FIG. 2) and surrounding fracture area 25 (25a FIG. 2).

Alternatively, fracturization and/or rubblization can be accomplished by conventional means such as hydraulic, explosive means and the like. To provide additional void space, if necessary, further leaching can be conducted.

Finally, a kerogen-pyrolyzing fluid such as steam is circulated from well borehole 11 (FIG. 1) through the

rubblized zone 24 and fractured zone 25 of oil shale formation 9 and out of well borehole 12. Hydrocarbon materials are then recovered from the heated fluid circulating out of well borehole 12 by means well known in the art. Removal of hydrocarbons from the oil shale provides additional void space enlarging the original rubblized zone, perpetrating the process. Similar techniques can be applied to single wells as shown in FIG. 2.

Conventional equipment and techniques, such as heating means, pumping means, separators and heat exchangers may be used for pressurizing, heating, injecting, producing and separating components of the heated fluid circulating through the oil shale formation 9. The production of the fluid may be aided by down-hole pumping means, not shown, or restricted to the extent necessary to maintain the selected pressure within the oil shale formation 9.

The fluid circulated through rubblized zone 24 and fractured zone 25 (FIG. 1) to recover oil shale from oil shale formation 9 may comprise any heated gas, liquid or steam. Oil shale reactive properties may also be imparted to the circulating fluid as discussed hereinabove.

Where the oil shale formation contains a zone rich in nahcolite in which zone the nahcolite occurs in the form of adjacent but discrete nodules or lenses 31, or the like, the present process is applied as described above. In this situation, the caverns comprise a network of relatively small cavities that are interconnected by fractures.

I claim as my invention:

1. A method of producing hydrocarbons from a subterranean oil shale formation containing at least one nahcolite-rich containing zone comprising the steps of:

35

- a. providing at least one well borehole extending into the nahcolite-containing zone of the oil shale formation;
- b. injecting into the nahcolite-containing zone via the borehole a nahcolite solvent having a temperature sufficient to cause thermal fracturing of oil shale in the oil-shale formation, and thereby simultaneously leaching nahcolite from the nahcolite-containing zone and thermally fracturing oil shale to create a zone of communicating cavities in the oil shale formation;
- c. injecting a pyrolyzing fluid into cavities zone (b) to effect spalling and rubblization of oil shale; and
- d. recovering hydrocarbons from the pyrolyzing fluid.

2. The method of claim 1 wherein at least two wells penetrate the formation one of which functions as an injection well and one as a production well.

3. The method of claim 1 wherein the nahcolite solvent is hot aqueous fluid injected via an injection well into the nahcolite-rich zone under hydrofracturing conditions to leach out nahcolite and fracture the leached zone area and wherein the pyrolyzing fluid is steam.

4. The method of claim 3 wherein the nahcolite is removed by steam used also to effect hydrocarbon recovery.

5. The method of claim 1 wherein nahcolite solvent is an aqueous fluid.

6. The method of claim 5 wherein the aqueous fluid is non-acidic.

7. The method of claim 5 wherein the pyrolyzing fluid is a non-aqueous fluid.

UNITED STATES PATENT OFFICE
CERTIFICATE OF CORRECTION

Patent No. 3,779,601 Dated December 18, 1973

Inventor(s) METHOD OF PRODUCING HYDROCARBONS FROM AN OIL SHALE
FORMATION CONTAINING NAHCOLITE.

It is certified that error appears in the above-identified patent
and that said Letters Patent are hereby corrected as shown below:

In the specification:

Column 3, lines 17 and 18, change "through two caverns"

to -- through the cavern --.

In the claims:

Claim 1, line 3, delete "rich".

Claim 2, line 2, insert a comma between the words "formation"

and "one".

Claim 4, line 1, change "claim 3" to -- claim 1 --.

Claim 4, lines 3 and 4, change "to effect hydrocarbon

recovery" to -- as a pyrolyzing fluid --.

Signed and sealed this 9th day of July 1974.
